SIZING METHOD AND MACHINE

Oliver E. Gibson, Chicago, Ill., assignor to United States Gypsum Company, Chicago, Ill., a corporation of Illinois

Application December 23, 1935, Serial No. 55,751

12 Claims. (Cl. 164—6.5)

This invention relates to sizing methods and machines, and has reference more particularly to a method of and machine for changing the width of sheets of flattened expanded metal to a size suitable for welding to steel shelf frames.

In the manufacture of shelves for mechanical refrigerators, stoves, etc., such as those disclosed in patent to A. C. Griffith, No. 1,961,144, it is difficult to roll the expanded metal flat so that the finished size is such that the bonds lie directly over the frame bars to which they are welded. To produce this result, it is desirable to employ a sizing operation subsequent to the rolling operation, so that the bonds register precisely with the frame bars to which they are welded.

An object of this invention therefore, is to provide a method of changing the width of a sheet of flattened expanded metal subsequent to the flattening operation, so that the bonds will register exactly with a steel frame to which they are subsequently welded.

Another object of the invention is to provide a machine suitable for carrying out the above sizing method; also to improve sizing methods and machines in other respects hereinafter specified and claimed.

Reference is to be had to the accompanying drawings forming a part of this specification, in which

Fig. 1 is a plan view of my improved machine for sizing flattened expanded metal.

Fig. 2 is a sectional elevation through the machine taken on line 2—2 of Fig. 1.

Fig. 3 is a sectional elevation through the machine taken on line 3—3 of Fig. 1.

Fig. 4 is a fragmentary sectional view taken through the operating levers of the machine, and

Fig. 5 is perspective view of a finished shelf made by the use of the sized flattened expanded metal.

My improved sizing machine consists of a plurality of spaced slats 10 of metal or other material, which form a table, the ends of said slats being secured on frame members 11 and 12. Vertical standards 13 support the frame members 11 and 12 on the floor 14, said standards being provided with horizontal brace members 15 somewhat above the floor. Edge slats 16 and 17 of the table are spaced above angle frame members 18 and 19, respectively, to receive the ends of a fixed bar 20 and a slidably mounted bar 21. A series of fixed pins 22 are secured to the bar 20, and a series of pins 23 are secured to the bar 21, said pins extending upwardly between the slats 10 to receive the edges of a strip of flattened ex-

panded metal 24 which is to be sized. Each of the pins 22 and 23 engages in one of the loops of the flattened expanded metal so that when the slidably bar 21 is moved toward or away from the fixed bar 20, the width of the expanded metal 24 is decreased or increased respectively to exactly the width desired in the finished sheet so that the bonds of the metal register exactly with the shelf frame 26 to be welded thereto to form the finished shelf.

In order to move the bar 21 longitudinally of the slats 10, I provide rock shafts 27 and 28 which are rotatably mounted in bearings 29 secured to the framework of the machine by bolts 30. Levers 31 and 32 are secured to the shafts 27 and 28, and connecting rods 33 and 34 connect the levers 31 and 32 to clevises 35 and 36, respectively, which are connected by bolts 37 to opposite ends of the bar 21. The shafts 27 and 28 are maintained in coaxial alignment by a section 38 on the inner end of shaft 28 which rotatably telescopes into a bearing hole 39 formed in the inner end of shaft 27. An operating lever 41 is secured to the inner end of shaft 27 and extends closely adjacent a similar lever 42 which is secured to the inner end of shaft 28. An outstanding handle 43 is secured to the outer end of lever 41 and a handle 44 is secured to the outer end of lever 42 so that the two handles 43 and 44 are normally in coaxial relation. A locking pin 45 extends coaxially through the handle 44, its inner end normally engaging in a receiving socket 46 formed in the inner end of handle 43 so as to keep the two handles in coaxial relation to move both ends of bar 21 an equal distance when the levers 41 and 42 are rocked, thus causing both ends of the strip of expanded metal 24 to be stretched or compressed equally. In some cases due to irregularities in the rolling or flattening operation, it is necessary to change the width of one end of the strip 24 slightly more than the other end to insure that the bonds on each edge of the strip will return to exactly parallel relation after the levers 41 and 42 release the pins 23. To accomplish this, the pin 45 is withdrawn from the socket 46 by manipulating a head 48 on the outer end of pin 45, the outer movement of said pin being limited by a stop pin 49 operating in a slot 50 formed in the handle 44. The levers 41 and 42 may then be rocked independently to provide the exact sizing result desired. The workman preferably makes suitable marks or indicia on the tops of the slats 10 to indicate the finished width of the strip 24 which is desired and the levers 41 and 42 are manipulated until this finished width is ob-

- tained, either by compressing or stretching the strip as needed. Connecting rods 33 of different lengths may be substituted in the machine when expanded metal strips 24 of substantially different widths are to be sized. This method of sizing produces strips of flattened expanded metal in which the bonds on opposite longitudinal edges are exactly parallel to register exactly with the shelf frame 26 to which they are welded.
- 10 I would state in conclusion, that while the illustrated example constitutes a practical embodiment of my invention, I do not wish to limit myself precisely to these details, since manifestly the same can be considerably varied without departing from the spirit of the invention as defined in the appended claims.
- Having thus described my invention, I claim as new and desire to secure by Letters Patent:
1. The method of producing a sheet of sized flattened expanded metal, which method includes applying along opposite edges of a sheet of flattened expanded metal, transverse forces acting in the plane of said sheet, said forces being proportioned in directions, points of application and magnitudes to shape said sheet to a predetermined size.
  2. The method of producing a sheet of sized flattened expanded metal, which method includes applying at a plurality of points along opposite edges of a sheet of flattened expanded metal, transverse forces acting in the plane of said sheet, said forces being proportioned in directions, points of application and magnitudes to shape said sheet to a predetermined size.
  3. The method of producing a sheet of sized flattened expanded metal, which comprises flattening expanded metal so that all bonds and strands lie in substantially a single plane, and applying transverse forces acting in the plane of said sheet at each end thereof, said forces being so proportioned in directions and magnitudes as to change the width of each end of said sheet to fit a peripheral frame member.
  4. In a machine for sizing a sheet of flattened expanded metal, a series of fixed pins for engaging one edge of said sheet, a slidably mounted bar having a series of pins for engaging the opposite edge of said sheet, and means for moving each end of said slide bar independently of the other end so as to independently change the width of each end of said sheet to a predetermined size.
  5. In a machine for sizing a sheet of flattened expanded metal, a series of fixed pins for engaging one edge of said sheet, a slidably mounted bar having a series of pins for engaging the opposite edge of said sheet, a pair of rock levers, a link connecting each of said levers with an end of said slide bar, and means for causing said levers to rock independently or in unison so as to change the width of said sheet to a predetermined size.
  6. In a machine for sizing a sheet of flattened expanded metal, a series of fixed pins for engaging one edge of said sheet, a slidably mounted bar having a series of pins for engaging the opposite edge of said sheet, a pair of rock levers, a link connecting each of said levers with an end of said slide bar, said levers being adapted

to rock independently so as to change the width of each end of said sheet to a predetermined degree, and means for interlocking said levers together to rock in unison.

7. In a machine for sizing a sheet of flattened expanded metal, fixed means for holding one edge of said sheet, movable means for engaging the opposite edge of said sheet, and means for independently actuating the opposite ends of said movable means to change the width of each end of said sheet to a predetermined degree.

8. The art of manufacturing shelves of flattened expanded metal, which comprises providing a peripheral frame member of metal, rolling a sheet of expanded metal to flatten the bonds and strands to produce a sheet having an area somewhat different than the area of said frame member, sizing said sheet of flattened expanded metal to an area substantially equal to that of said frame member, by applying to the edges of said sheet transverse forces acting in the plane of said sheet, said forces being proportioned in directions, points of application and magnitudes to shape said sheet to said size and area and securing the edges of said sheet to said frame member.

9. The method of forming sized sheets of flattened expanded metal, which comprises slitting a sheet of metal to form strands and bonds, stretching said sheet to open the meshes and produce expanded metal, rolling said sheet to flatten the bonds and strands, and again stretching said flattened sheet by applying at a plurality of points along opposite edges of said sheet, transverse forces acting in the plane of said sheet, said forces being proportioned in directions, points of application and magnitudes to shape said sheet to predetermined size and area equal to that of a peripheral frame member.

10. The method of producing sized sheets of flattened expanded metal, which comprises flattening expanded metal by rolling, and subsequently stretching or compressing the sheet as the case may be by applying at a plurality of points along opposite edges of said sheet, transverse forces acting in the plane of said sheet, said forces being proportioned in directions, points of application and magnitudes to shape said sheet to predetermined size so as to fit a peripheral frame.

11. The method of producing sized sheets of flattened expanded metal produced by rolling standard expanded metal, which comprises compressing the sheet by applying along opposite edges of said sheet, transverse forces acting in the plane of said sheet, said forces being proportioned in directions, points of application and magnitudes to shape said sheet to a predetermined size so as to fit a peripheral frame.

12. In a machine for sizing a sheet of flattened expanded metal, means for holding each edge of said sheet, and means for independently changing the distance between said holding means at each end thereof so as to stretch or to contract said sheet as the case may be, so that the width of said sheet is changed to a predetermined degree.

OLIVER E. GIBSON.
